HYDRAULICALLY OPERATED MECHANICAL
KNEE LOCK

Orvin S. Johnson, Manhattan Beach, and Fred T. Roberts, Los Angeles, Calif., assignors to Northrop Aircraft, Inc., Hawthorne, Calif., a corporation of California

Application August 5, 1948, Serial No. 42,636

10 Claims. (Cl. 3—2)

1 The present invention relates generally to artificial legs, and more particularly to the type of leg used in above-knee amputations, wherein the lower leg component is connected by a knee joint to an upper leg component that is attached to the stump. In artificial legs of this class, it is essential to provide a means in the knee joint mechanism for locking the knee during certain phases of the walking cycle, so as to prevent involuntary flexion of the leg.

Locomotion studies of human gait have established the fact that during each complete walking cycle, the natural knee locks in two separate positions; the first being when the heel strikes the ground at the forward end of the leg swing, and the second being at the rear end of the leg swing, when the weight is momentarily supported on the toes during the push-off phase. Between the first and second locked positions, or while the weight of the body is supported on the leg, the knee unlocks and flexes slightly to cushion the shock of impact. One of the principal objects of the invention, therefore, is to duplicate this sequence of actions, and to provide a mechanism which exerts a positive locking action on the knee when the heel strikes the ground, and again during the push-off phase when the weight is carried on the toes.

Another object of the invention is to provide a mechanism responsive to the sudden application of a force on the heel or toe of the foot, for locking the knee at any position of flexion, so as to prevent the leg from collapsing under the wearer in the event of stumbling or momentarily losing balance, and thereby give the amputee opportunity to recover.

Still a further object of the invention is to provide a knee lock actuating mechanism which is silent in operation, substantially free from lost motion, and possessed of great flexibility for purposes of installation. This object is accomplished with a novel hydraulic force-transmitting system which is actuated by cam means on the foot, whereby angular displacement of the foot about the ankle, or of the hinged toe portion with respect to the foot, causes a force to be applied to the lock which locks the knee against flexion. The advantages of this arrangement are that the hydraulic system eliminates the objectionable mechanical noise experienced with linkage; and having no clearances to take up, is entirely free from loose play. Furthermore, the inherent flexibility of a hydraulic transmission system makes it admirably suited to installation in artificial legs, due to the wide variations in length

encountered between the ankle and knee of different individuals. Such variations in length are immaterial to a hydraulic system, and are easily accommodated by cutting the tubing to the desired length, or bending the tubing to fit the installation. Mechanical linkages, on the other hand, require parts of different length, and must be carefully adjusted by skilled limb fitters. Another advantageous feature of the hydraulic system is that the frictional loss is less than in a mechanical linkage, with a corresponding reduction in wear.

The foregoing and other objects and advantages of the present invention will become apparent to those skilled in the art upon consideration of the following detailed description of the preferred embodiment thereof, reference being had to the accompanying drawings, wherein:

Figure 1 is a side elevational view of an artificial leg embodying the principles of the invention;

Figure 2 is a front elevational view of the same; Figure 3 is an enlarged vertical section through the knee joint, taken substantially along the line 3—3 in Figure 2;

Figure 4 is an enlarged sectional view through the ankle joint, taken at 4—4 in Figure 1;

Figure 5 is a reduced sectional view, taken at 5—5 in Figure 4, showing the manner in which the knee lock is actuated by plantar flexion of the foot;

Figure 6 is a sectional view, taken at 6—6 in Figure 4, showing the manner in which the knee lock is operated by upward deflection of the hinged toe portion of the foot;

Figure 7 is an enlarged sectional view through the knee joint, taken at 7—7 in Figure 2; and

Figure 8 is another sectional view through the knee, taken at 8—8 in Figure 2.

In the drawings, the artificial leg representing the preferred embodiment of the invention is designated in its entirety by reference numeral 10, and is seen to comprise upper and lower leg components 11 and 12, respectively, which are connected together by a knee joint 13 for relative swinging movement. Attached to the bottom end of the lower leg component 12 by an ankle joint 14 is a foot 15 having a hinged toe portion 16. The upper leg component 11 may take any desired form, and in the present instance comprises a suction socket 20 of the type which is adapted to be held on the stump by a slight suction pressure within the socket.

Mounted on the bottom end of the suction socket 20 in any suitable manner is a base mem-

ber 21 having downwardly extending cylindrical side walls that are cut out in the front and rear to form laterally spaced bracket arms 22 which support the ends of a transversely disposed tubular shaft 23. The shaft 23 has splines or serrations 24 formed in its external surface which extend from one end thereof to the other, and the ends of the shaft are received within serrated holes in the bracket arms 22, so that the shaft is rigidly held against rotation with respect thereto. Cap screws 25 are screwed into the ends of the shaft 23 and engage the outer surfaces of the bracket arms 22 to confine the shaft between the arms. Internally serrated bearing sleeves (not shown) are inserted over the ends of the shaft 23 adjacent the inner surfaces of the arms 22, and journaled on these sleeves for fore and aft swinging movement is a yoke member 26.

The yoke member 26 has a split-clamp sleeve portion 30 which is inserted over the top end of a pylon tube 51 of the lower leg component 12, and is securely clamped thereto by bolts 32. The upper portion of the yoke 26 is bifurcated, forming laterally spaced, upwardly extending arms 33 and 34 which are drilled and bushed to receive the aforementioned bearing sleeves on the shaft 23. The lower leg component 12 need not necessarily be of the pylon construction shown, but might take any other desired form. In the case of the pylon construction shown herein, the tube 31, knee 13, and ankle 14 may be enclosed by a cosmetic shell for the sake of improved appearance and to protect the clothing of the wearer.

The knee joint 13 is adapted to be locked against flexion under certain conditions, and to this end is provided with a self-energizing, friction lock 35 comprising a brake band 36 and C-shaped anchor link 37. The brake band 36 encircles and fits snugly around a tubular shoe or sleeve 40 which is inserted over the shaft 23 and serrated internally to mesh with the serrations 24. The two ends of the brake band 36 are brought together in a slightly spaced, overlapping relationship, as shown in Figure 3, and are slotted out at 41 and 42 to receive the large end of the anchor link 37, to which they are attached by pins 43 and 44. The pins 43 and 44 are spaced apart in a generally radial direction with respect to the axis of shaft 23, for reasons which will be explained shortly.

The small end of the anchor link 37 is connected by a pin 45 to the top end of a link 46, the bottom end of which is swingably connected to a bolt 50 extending transversely between the yoke arms 33, 34. The link 46 provides a floating anchorage for the anchor link 37, and enables the brake band 36 and large end of the anchor link, to which it is attached to rotate slightly about the sleeve 40.

The anchor link 37, in addition to preventing the brake band 36 from turning on the sleeve 40, serves also to clamp the brake band tightly around the sleeve, thereby locking the yoke 26 and its lower leg component 12 to the stationary knee shaft 23. This locking action results when the anchor link 37 is rocked in a counterclockwise direction about its right-hand end (Figure 3), which has the effect of drawing the ends of the brake band 36 together and wrapping the brake band tightly around the sleeve 40. A compression coil spring 51 that is attached to the underside of the anchor link 37 and bears slidably on the outer surface of the brake band 36, urges the anchor link away from the brake band, which has the effect of rocking the anchor link

in a clockwise direction about its right-hand end to release or unlock the brake band from sleeve 40.

The lock 35 is actuated by rotating the brake band 36 slightly in a clockwise direction about the sleeve 40, which carries the right hand end of the anchor link 37 downwardly with it. Pins 43 and 44, being fixed to the anchor link 37, move in concentric arcuate paths about pin 45 as a center; and pin 45, in turn, shifts slightly along an arcuate path about pin 50 as a center to accommodate the change in position of the anchor link. The pins 43 and 44 are also fixed to the ends of the brake band 36, however, and the rotational movement of the latter is about the axis A of shaft 23 as a center. Hence, there is a conflict in the path followed by pins 43 and 44 as a result of their attachment to both the anchor link 37 and to the ends of the brake band 36.

Considering first the path of pins 43, 44 about center A as a center, we note that the distance of pin 44 from center A is slightly more than half again as much as the distance of pin 43 from center A, which means that the linear travel of pin 44 would have to be approximately half again that of pin 43 if the two pins were to remain in the relative positions as the brake band turns on the sleeve 40. However, the pins 43, 44 are also constrained to swing about pin 45 as a center, and in this case the distance of pin 44 from pin 45 is only about one-fourth again as much as the distance of pin 43 from pin 45; hence the linear travel of pin 44 is only one-fourth again that of pin 43. Since the pins 43, 44 are immovably fixed to the anchor links 37, it follows that the travel of pin 44 with respect to pin 43 is governed by the anchor link, and this means that the travel of pin 44 with respect to that of pin 43 is less than the amount required to maintain the two pins in the same relative position with respect to the brake band. The net result is that when the brake band 36 is rotated in a clockwise direction about the sleeve 40, the pin 43 moves downwardly with respect to pin 44, which causes the brake band to wrap tightly around the sleeve and thereby lock the knee against flexion. One characteristic of this type of lock is that it is self-energizing in nature, and therefore tends to lock more tightly as the load on the knee joint is increased.

The lock 35 is held in the released or unlocked condition by means of a compression coil spring 52 which encircles a bolt 53 and bears at its bottom end against a bracket 54 that is secured by bolt 55 to the arms of yoke 26 at the back side thereof. The top end of spring 52 bears upwardly against the bight of a U-shaped clevis 56 which is fastened to the extended ends of pin 44. Bolt 53 passes through holes 60 and 61 in the clevis 56 and bracket 54, respectively, and is free to slide through either of the same when the spring 52 is compressed. A nut 62 is screwed onto the bottom end of bolt 53 and engages the bracket 54 to limit the upward travel of the bolt.

The lock 35 is adapted to be operated by a hydraulic actuating mechanism consisting of a work cylinder 65 and a hydraulic master cylinder 66 which are connected together by a fluid line 67 of aluminum tubing or the like. The cylinders 65 and 66 may take any desired form, but are preferably of the construction illustrated, embodying thin-walled, flexible metal bellows 68 and 69 of the type known as "Sylphon" bellows, which provide a leak-proof, closed system. The bellows 68 of the work cylinder 65 is contained within a cylindrical chamber 70 in a housing 71, and the

latter is secured by bolts 72 to yoke member 26 between the arms 33, 34 thereof. One end of the bellows 68 is soldered to a plug 73 which is screwed into the bottom end of the chamber 70. The top end of the bellows is soldered to a movable member 74 having an upwardly extending cylindrical stem 75 which extends through and is slidable within a bore 76 in the top end of the housing.

Extending part way down into the stem 75 along the axis thereof is a tapped hole 80, into which an eye bolt 81 is screwed. The eye bolt 81 has a horizontally elongated aperture 82 formed in its top end, and a pin 83 extends through the slot to connect the eye bolt to the front end of a lever arm 84. The lever arm 84 is pivoted intermediate its ends on a transverse pivot bolt 85, and the rear end of the lever arm is connected by a pin 86 to an upwardly extending link 90. The top end of the link 90 is attached to the brake band 36 by a pin 81, which is located so that a downward pull of the link 90 causes the brake band to rotate in a clockwise direction about its supporting sleeve. Thus, the brake 35 is actuated to lock the knee against flexion when the bellows 68 of the work cylinder 65 is expanded, causing the movable member 75 to move upwardly and thereby by pulling the link 90 downwardly to rotate the brake band in a clockwise direction.

The plug 73 closing the bottom end of the bellows chamber 70 is provided with a tapped hole 92 opening into the bellows 68, and screwed into this hole is the threaded stud 93 of a pipe coupling member 94. The tubing 67 extends downwardly from the cylinder 65 and around to the back of pylon 31, where it is connected at its bottom end by an elbow fitting 95 to the end of the housing 96 of master cylinder 66.

The cylinder housing 96 is disposed between two laterally spaced, vertical flanges 97 which are formed integral with and extend rearwardly from an ankle yoke 98 mounted on the bottom end of the pylon tube 31. The flanges 97 are formed with enlarged bearing bosses 99 in their lower ends, and these are drilled to receive a transverse ankle pivot shaft 100. The shaft 100 extends beyond the bearing bosses 99, as shown in Figure 4, and its ends are journaled in bushings 101 which are pressed into apertures in the arms 102 of a U-shaped bracket 103. The bracket 103 is disposed within a cavity 104 in the foot 15, and is provided with a downwardly extending threaded stud 105 which extends through a hole 106 in the foot and is secured by a nut 107.

At the front end of the yoke member 98 between the flanges 97 is an upwardly inclined shelf 110 which is engageable with the top end of a rubber instep bumper 111 that is set into a slight recess in the top surface of a shelf portion 112 of the foot. A horizontal shelf 113 at the rear end of the yoke 98 is engageable with the top end of a rubber heel cushion 114. The two cushions 111 and 114 engage their respective shelves to locate the foot in its normal position, as shown in Figure 1. The instep cushion 111, being rather short, permits only a very limited amount of dorsiflexion of the foot, while the heel cushion 114, being considerably longer, is more resilient and permits a greater degree of plantar flexion.

The housing 96 of the master cylinder 66 is secured to the flanges 97 of the ankle yoke 98 by two bolts 115 in an upwardly and rearwardly inclined position, with its axis intersecting the axis of the ankle shaft 100. A cylindrical chamber 116 is formed in the housing 96, and the bellows 69 is disposed therein. The top end of the cham-

ber is threaded internally to receive a screw-threaded plug 120 which, in turn, is provided with a tapped hole 119 opening into the interior of the bellows 69, that receives the threaded stud 121 of the elbow fitting 95. The top end of the bellows 69 is soldered to the plug 120, and the bottom end of the bellows is soldered to a movable member 122 having a stem 123 which extends down through an opening 124 in the bottom end of the housing. The movable member 122 has a tapped hole extending part way up from the bottom end thereof, and screwed into this hole is the threaded shank of a yoke member 125.

The lower end of the yoke 125 is bifurcated to provide two laterally spaced arms that are drilled to receive a transverse shaft 126, the ends of which project beyond the yoke arms and are slidably disposed within guide slots 130 in a cylindrical extension 131 of the housing 96. Journalled on the shaft 126 between the arms of yoke 125 is a cam follower roller 132 which rides on the peripheries of two cams 133 and 134 that are arranged side by side on shaft 100.

Cam 133 is preferably of the configuration shown in Figure 5, and is provided with an arm portion 135 which is secured by a screw 136 to a bracket 140 projecting upwardly from the bottom of the cavity 104 in the foot. The aperture in arm 135 through which the screw 136 projects is preferably slotted, as shown, to permit a limited amount of angular adjustment of the cam about the shaft 100. A lobe 141 on the periphery of the cam 133 is normally located just below the axis of the master cylinder 66 when the foot is positioned as shown in Figure 1, so that the roller 132 bears on the low portion of the cam immediately at the foot of the rise leading up to the top of lobe 141. Being attached to the foot 15, the cam 133 is constrained to rotate with the foot about the shaft 100 when the foot is deflected in plantar flexion, as shown in Figure 5. This is the condition which is obtained when the weight is thrown on the heel at the end of the forward swing phase of the leg during the walking cycle. As the cam 133 rotates with the foot, the lobe 141 raises the roller 132 and compresses the bellows 69, which forces fluid through the line 67 to the bellows 68 and causes the latter to expand, thereby operating the lock 35.

Cam 134 is journalled for rotation on shaft 100 and is connected by a pin 147 to the rear end of a turn buckle link 145; the front end of said link being connected by a pin 148 to a bracket 146 on the hinged toe portion 16. The toe portion 16 is connected to the foot 15 by a transverse hinge 150 at the bottom of the foot, and is free to be deflected upwardly, as in Figure 6, when the weight of the body is momentarily supported on the toes during the push-off phase of the walking cycle. As the toe portion 16 deflects upwardly the bracket member 146 swings in a clockwise direction about the hinge 150, pushing the turn buckle link 145 to the right, and thereby rocking the cam 134 in a clockwise direction. The cam 134 is provided with a lobe portion 151 which is normally positioned just ahead of the roller 132, or in a counterclockwise direction with respect thereto, as seen in Figures 5 and 6, so the roller is positioned on the low portion of the cam at the foot of the incline leading to the top of the lobe 151. Thus, when the toe portion 16 is deflected upwardly, the cam 134 is rocked in a clockwise direction, causing the roller 132 to ride up on the lobe 151, and thereby compressing the bellows 69 to operate the lock 35.

From the foregoing description, it will be seen that the bellows 69 of the master cylinder 66 is normally fully extended when the foot 15 and toe portion 16 are in their normal positions, as shown in Figure 1, and is compressed either when the foot 15 is displaced in plantar flexion, or when the toe portion 16 is deflected upwardly. In the one case, compression of the bellows 69 is caused by roller 132 riding up onto lobe 141 of cam 133; while in the other case, the roller rides up onto lobe 151 of cam 134. Such compression of the bellows 69, of course, produces a corresponding extension of the bellows 68 in the work cylinder 65, thereby operating the lock 35. Wedge-shaped cushions 152 of sponge rubber or other resilient material are disposed between the adjacent faces of the toe portion 16 and foot 15 on opposite sides of the bracket 146 to provide resilient bumpers for yieldingly holding the toe portion 16 in extended position. These bumpers 152 are compressed when the toe portion 16 is deflected upwardly, as in Figure 6.

In order to simulate more closely the forward swinging rate of the natural leg during the walking cycle, we have embodied a friction brake 160 in the knee joint 13, which serves to check or slightly retard the free forward swinging movement of the lower leg with respect to the upper leg. The friction brake 160 comprises a split brake band 161 that encircles the sleeve 40 alongside the lock 35. The brake band 161 is provided with an ear 162 having an open-end slot 163 formed therein, extending radially from the axis of the knee shaft; and disposed within this slot is an anchor pin 164 which projects inwardly from the yoke arm 34 and prevents the brake band from turning. At the top of the brake, the two ends of the brake band 161 are turned outwardly to form ears 165 and 166 which are connected by an adjusting screw 170. The screw 170 extends through a smooth hole in the ear 165 and is threaded into a tapped hole in ear 166, so that when the screw is turned, the ears 165, 166 are drawn together or spread apart to increase or decrease the tension of the brake band on the sleeve 40.

On the opposite sides of the lock 35 from friction brake 160 is a limit stop member 172, shown to best advantage in Figure 8. The member 172 has a serrated hole 173 formed therein which receives the serrated shaft 23, whereby the two members are locked together against relative rotation. Two angularly related shoulders 174 and 175 are provided on the member 172, and these are respectively engageable with a resilient bumper strip 176 lying on a horizontal shelf 180 on the yoke arm 33, when the lower leg is in the solid-line extended position, or in the fully flexed position shown in phantom line. It might be mentioned at this point that when the leg is fully extended, the axis of the hinge pivot is located posterior to the vertical line of the center of gravity of the body, causing the pivot to go past the centerline as the leg is extended, giving about 2° of hyper-extension, which stabilizes the knee joint.

It is believed that the construction and operation of the mechanical knee lock and its hydraulic actuating mechanism will be fully understood from the foregoing description, and that the many advantageous features thereof will be readily appreciated by those skilled in the art. While we have shown and described in considerable detail what we believe to be the preferred form of our invention, it is to be understood that

such details are not restrictive, and that various changes may be made in the shape and arrangement of the several parts without departing from the broad scope of the invention, as defined in the appended claims.

5 We claim:

1. In an artificial leg having an upper leg component, a lower leg component swingably connected thereto by a knee joint, and a foot pivotally connected to said lower leg component by an ankle joint, the combination of a mechanical friction lock operatively connected to said knee joint to lock the same against flexion movement, a hydraulic work cylinder mounted on one of said leg components and connected to said lock to operate the same, and a hydraulic master cylinder mounted on said lower leg component and connected by a fluid line to said work cylinder, said master cylinder being mechanically linked to said foot so that pivotal movement of the foot about said ankle joint from a predetermined normal position causes said master cylinder to be compressed, thereby applying fluid pressure to said work cylinder to operate the lock.
2. In an artificial leg having an upper leg component, a lower leg component swingably connected thereto by a knee joint, and a foot pivotally connected to said lower leg component by an ankle joint, the combination of a mechanical friction lock operatively connected to said knee joint to lock the same against flexion movement, a spring attached at one end to one of said leg components and operatively connected at the other end to said lock so as to exert a pressure thereon tending to release the lock, and hydraulic actuating means operatively connected to said lock in opposition to said spring, said actuating means including a hydraulic work unit and a fluid pressure generator, both mounted on said lower leg component, said fluid pressure generator being mechanically linked to said foot so that the fluid pressure in the system is increased when said foot is pivoted about said ankle joint from a predetermined normal position, and said work unit being operable to overcome said spring and lock said knee when the fluid in the system exceeds a predetermined pressure.
3. In an artificial leg having an upper leg component, a lower leg component swingably connected thereto by a knee joint, and a foot pivotally connected to said lower leg component by an ankle joint, the combination of a mechanical friction lock operatively connected to said knee joint to lock the same against flexion movement, a hydraulic work unit mounted on one of said leg components and comprising an expansible chamber having a movable member connected to said lock to operate the same, another hydraulic unit mounted on said lower leg component and comprising an expansible chamber having a movable member, a fluid line connecting the expansible chamber of said last-named unit with that of said first-named unit, a cam member fixedly mounted on said foot for angular movement therewith about said ankle joint, and a follower engaging said cam and operatively connected to said movable member of said last-named hydraulic unit, said cam member being so designed that angular displacement of said foot about said ankle joint from a predetermined normal position causes said follower to compress said chamber of said last-named unit with corresponding extension of the chamber of said first-named unit to operate said lock.
4. In an artificial leg having an upper leg com-

ponent, a lower leg component swingably connected thereto by a knee joint, a foot pivotally connected to said lower leg component by an ankle joint, and a hinged toe portion on the front end of said foot, the combination of a mechanical friction lock operatively connected to said knee joint to lock the same against flexion movement, and hydraulic actuating means for operating said lock responsive to angular displacement of said toe portion about its hinge axis from the normal position, said actuating unit including a hydraulic work unit and a fluid pressure generator, both mounted on said lower leg component, said fluid pressure generator being mechanically linked to said toe portion so that the fluid pressure in the system is increased when said toe portion is bent upwardly about its hinge axis, and said work unit being operable to lock said friction lock when the fluid pressure in the system exceeds a predetermined pressure.

5. In an artificial leg having an upper leg component, a lower leg component swingably connected thereto by a knee joint, a foot pivotally connected to said lower leg component by an ankle joint, and a hinged toe portion on the front end of said foot, the combination of a mechanical friction lock operatively connected to said knee joint to lock the same against flexion movement, a hydraulic work cylinder mounted on one of said leg components and connected to said lock to operate the same, and a hydraulic master cylinder mounted on said lower leg component and connected by a fluid line to said work cylinder, said master cylinder being mechanically connected to said toe portion in a manner such that hydraulic pressure in the system is increased when said toe portion is deflected upwardly about its hinge axis from the normal position.

6. In an artificial leg having an upper leg component, a lower leg component swingably connected thereto by a knee joint, a foot pivotally connected to said lower leg component by an ankle joint, and a hinged toe portion on the front end of said foot, the combination of a mechanical friction lock operatively connected to said knee joint to lock the same against flexion movement, a hydraulic work cylinder mounted on said lower leg component and connected to said lock to operate the same, a hydraulic master cylinder mounted on said lower leg component and connected by a fluid line to said work cylinder, a rotatable cam member coaxial with said ankle joint and connected to said hinged toe portion, whereby angular movement of said toe portion about its hinge axis causes said cam member to rotate, and a follower engaging said cam and operatively connected to said master cylinder to actuate the same, said cam member being designed so that said work cylinder is compressed by said follower when said toe portion is deflected upwardly about its hinge axis, thereby operating said lock.

7. In an artificial leg having an upper leg component, a lower leg component swingably connected thereto by a knee joint, a foot pivotally connected to said lower leg component by an ankle joint, and a hinged toe portion on the front end of said foot, the combination of a mechanical friction lock operatively connected to said knee joint to lock the same against flexion movement, a hydraulic work cylinder mounted on said lower leg component and connected to said lock to operate the same, a hydraulic master cylinder mounted on said lower leg component and connected by a fluid line to said work cylinder,

der, rotatable cam means coaxial with said ankle joint and connected to said foot and to said hinged toe portion, and a follower engaging said cam means and operatively connected to said master cylinder, said cam means being designed so that said work cylinder is compressed by said follower when said foot is deflected angularly about said ankle joint from a predetermined normal position, or when said toe portion is bent upwardly about its hinge axis, thereby operating said lock.

3. In an artificial leg having an upper leg component, a lower leg component swingably connected thereto by a knee joint, a foot pivotally connected to said lower leg component by an ankle joint, and a hinged toe portion on the front end of said foot, the combination of a mechanical friction lock operatively connected to said knee joint to lock the same against flexion movement, a hydraulic work cylinder mounted on said lower leg component and connected to said lock to operate the same, a hydraulic master cylinder mounted on said lower leg component and connected by a fluid line to said work cylinder, rotatable cam means mounted coaxial with the pivot axis of said ankle joint, said cam means being constrained to rotate with said foot when the latter is flexed, and being connected to said hinged toe portion for movement therewith when the toe portion is deflected upwardly about its hinge axis, and a follower engaging said cam means and operatively connected to said master cylinder, said cam means being so designed that said work cylinder is compressed by said follower when said foot is deflected angularly about said ankle joint from a predetermined normal position, or when said toe portion is deflected upwardly about its hinge axis, thereby operating said lock.

40. 9. In an artificial leg having an upper leg component, a lower leg component swingably connected thereto by a knee joint, a foot pivotally connected to said lower leg component for rotation about a transverse ankle shaft, and a hinged toe portion on the front end of said foot, the combination of a mechanical friction lock operatively connected to said knee joint to lock the same against flexion movement, a hydraulic work cylinder mounted on said lower leg component and connected to said lock to operate the same, a hydraulic master cylinder mounted on said lower leg component and connected by a fluid line to said work cylinder, a pair of cams arranged side-by-side on said ankle shaft, one of said cams being connected to said foot so as to rotate therewith when the foot is deflected, the other of said cams being journaled for rotation on said ankle shaft, link means connecting said other cam to said hinged toe portion, whereby said other cam is rotated when said toe portion is rotated about its hinge axis, and a follower engaging both of said cams and operatively connected to said master cylinder, said cams being designed so that said master cylinder is compressed by said follower when said foot is rocked about said ankle shaft from a predetermined normal position, or when said toe portion is deflected upwardly about its hinge axis, thereby operating said lock.

60. 70. 10. In an artificial leg having an upper leg component, a transverse knee shaft fixedly connected thereto, a lower leg component journaled for swinging movement on said knee shaft, a foot pivotally connected to said lower leg component for rotation about a transverse ankle shaft, and

11

a hinged toe portion on the front end of said foot, the combination of a self-energizing mechanical friction lock comprising a brake band encircling said knee shaft, an anchor link attached at one end to said lower leg component, both ends of said brake band being attached to the other end of said anchor link at points spaced apart in a generally radial direction relative to said knee shaft, said brake band tending to bind tightly around said knee shaft when said other end of said anchor link is moved in one direction about the knee shaft, and to release said knee shaft when moved in the other direction, a spring acting on said other end of said anchor link and urging the same in said other direction, a thin-walled, flexible metal bellows having a movable member at one end thereof connected to said brake band, whereby extension of said bellows causes said other end of said anchor link to move in said one direction against the pressure of said spring to operate said lock, another thin-walled, flexible metal bellows mounted on said lower leg component and connected by a fluid line to said first-named bellows, said last-named bellows having a movable member at one end thereof, a pair of cams arranged side-by-side on said ankle shaft, one of said cams being connected to said foot so as to rotate therewith, the other of said cams being journaled on said shaft for rotation with respect to said foot, link means connecting said other cam to said hinged toe por-

12

tion, and a follower engaging both of said cams and connected to said movable member of said last-named bellows, whereby said last-named bellows is compressed by said cams responsive either to angular deflection of said foot about said ankle shaft or to upward deflection of said toe portion about its hinge axis, said compression of said last-named bellows causing said first-named bellows to extend and thereby operate said lock.

ORVIN S. JOHNSON.
